UNITED STATES PATENT OFFICE.

HOWARD L. POWELL, OF NEW YORK, N. Y., AND BARNEY J. MIRACKY, OF LITTLE FERRY, NEW JERSEY, ASSIGNEES TO NATIONAL BISCUIT COMPANY, OF NEW YORK, N. Y., A CORPORATION OF NEW JERSEY.

DEPOSITING-MACHINE.

1,314,606.

Specification of Letters Patent.

Patented Sept. 2, 1919.

Application filed August 28, 1918. Serial No. 251,729.

To all whom it may concern:

Be it known that we, HOWARD L. POWELL and BARNEY J. MIRACKY, both citizens of the United States, the former residing in the 5 borough of Manhattan, city, county, and State of New York, and the latter residing at Little Ferry, in the county of Bergen and State of New Jersey, have invented certain new and useful Improvements in 10 Positing-Machines, of which the following is a specification.

Our invention relates to apparatus in which marshmallow, icing, or the like, is deposited on small circular cakes or like 15 goods, which are advanced in rows on a traveling carrier to the point at which the deposit is made, and then onwardly to the point at which they are removed from the carrier. The cakes are placed on the carrier 20 in parallel rows, preferably by feeding them on to flat trays which are placed in a continuous series on a traveling chain or chains which are advanced intermittently, the depositing device operating during each 25 period of rest of the carrier to make a deposit on the cakes which are arranged in a row beneath the spouts of the depositing device. Our present improvement consists in an 30 alining device which is actuated during each period of rest of the carrier to correct any faulty alinement, either lengthwise or transversely of the carrier, of the cakes which are about to receive a deposit. Such faulty alinement may be caused by the manner in 35 which the cakes are fed onto, or arranged on, the trays, or by the vibration to which they are subjected during the intermittent movement of the carrier. The travel of the cakes to the depositing device may be a distance 40 of a number of feet, especially if they have first to pass under another device, by which certain articles, such as candied fruits, are deposited on the cakes before the icing or marshmallow is placed thereon.

45 Our improved alining device comprises a member with depending fingers, which reciprocates lengthwise of the carrier, and approaches the row of cakes at rest immediately behind the depositing device, so that 50 each finger presses slightly against the inner rear curved edges of a pair of adjacent cakes, to separate them a spaced interval lengthwise of the row, and to push them for-

wardly into alinement at right angles to the travel of the carrier. The fingers then rise 55 slightly and return over the next row of cakes which is moving forward, the fingers moving forward again and lowering into position when the forward movement of the carrier has stopped. The adjusted row of 60 cakes moves forward one step into positions immediately below the spouts of the depositing device, while the alining device is moving back over the next row to the rear, the up and down movement of the alining 65 device preferably being obtained from a vertically reciprocating part of the depositing device, and its forward and back movement from the carrier feed, by a reversing connection. 70

In order that a clearer understanding of our invention may be had, attention is hereby directed to the accompanying drawings illustrating one embodiment of our invention and forming part of this application. 75 In the drawings, Figure 1 represents a side elevation of a machine equipped with our invention; Fig. 2 is a cross-section taken on line 2—2 of Fig. 1; Fig. 3 is a section taken on line 3—3 of Fig. 4; Fig. 4 is a partial 80 side elevation, partly shown in section, on an enlarged scale, of the cake-alining device; Fig. 5 is a partial top plan view, on an enlarged scale, showing the adjustment of a row of cakes by the alining device; and Fig. 85 6 is a partial side elevation, showing a modification of our invention.

Referring to the drawings, the apparatus illustrated embodies a frame indicated at 1, carrying sprocket-wheels, of which one is 90 shown at each end of the machine at 2 and 3. A flexible carrier, such as a chain or chains 4, runs over these sprockets, intermittent movement, in a clockwise direction, referring to Fig. 1, being transmitted thereto 95 from the shaft 5 of a ratchet wheel 6. A sprocket wheel 7 on shaft 5 is connected by a drive chain to a corresponding sprocket on the shaft of sprocket-wheel 2, shaft 5 being given a step-by-step movement by a pawl 8 100 100 which operates ratchet wheel 6. Pawl 8 is carried by an arm 9 centrally mounted for oscillation about shaft 5, arm 9 being oscillated by pivotal connection of its lower end with a connecting rod 10, the opposite end 105 of which is eccentrically connected, at 11, to

a gear 12. The latter is rotated by any suitable power connection, such as the gears indicated at 13, driven from motor 14.

The flexible carrier 4 is adapted to carry 5 a series of flat wooden trays which may be placed thereon with their transverse edges abutting against each other. The small round cakes 15 are deposited on the trays, in the machine illustrated, by a hopper 10 device 16, which is operated by a reciprocating member 17, connected for operation to a crank 18, which is oscillated by a link 19 connected to the upper end of the arm 9. The cakes may be deposited in rows on the 15 trays, the rows being separated by the distance the carrier moves forward each forward movement of pawl 8. The marshmallow or icing is deposited on the cakes by a depositing device comprising a hopper 20, 20 in which are mounted a plurality of tubes or barrels 21, 21, terminating in spouts 22, 22, the spouts being parallel to the cakes as they are positioned on the trays by the device 16, and equal to the number of cakes in 25 each row.

Each tube 21 contains a plunger 23, and all of the plungers are connected to a cross member 24 which is moved up and down by a link 25, on each side of the machine, the 30 lower end of which carries a roller 26. This is also rotatably secured to a crank 27, pivoted at 28, and bears on a cam 29 mounted on a stud 30, which rotates with spur gear 31, which is continuously rotated by gear 12. 35 The tubes 21 are also connected together by a cross member 32, which is reciprocated by links 33 on each side of the machine, each link being pivoted at 34 to a bell-crank 35 pivoted at 36 to the frame of the machine. 40 The lower end of each bell-crank carries a roller 37 which bears against a cam 38 rotating with gear 12. These constructions do not form part of our present invention and need not be described in further detail. The 45 result of the apparatus so far described is to cause the plungers 23 to move downward, to expel the marshmallow below the same, from spouts 22, each time rollers 26 pass over the high points 39 of cams 29, which 50 occurs at the end of each forward movement of the carrier. The tubes 21 are lifted a certain distance at the beginning of the forward movement of the carrier, that is, from the position of the parts shown in Fig. 1 55 more rapidly than the plungers 23 are lifted, the tubes again descending more gradually than the plungers during the return movement of pawl 8, and the consequent period of rest of the carrier. This movement is 60 arranged to provide a measured quantity of marshmallow or the like in the tubes below the plungers at the moments when the latter begin their expelling movements. As stated, another depositing device similar to that 65 just described, and similarly operated, may

be provided between the depositing device illustrated and the point at which the cakes are deposited or fed on the trays on the carrier, this additional depositing device being omitted from the drawings for the 70 sake of simplicity.

The device for alining the cakes comprises a frame 40 having depending fingers 41, as shown in Figs. 3, 4 and 5, adapted to press against the rear inner edges of the 75 cakes 15. Frame 40 is provided with forwardly-extending sleeve portions 42, 42, which are slidably mounted on rods 43, 43, which are fixedly secured to the cross member 32 of the depositing device. Frame 40 80 is reciprocated lengthwise of the carrier by means of arms on each side of the machine, one of which is shown at 44, pivoted, midway its length, to frame 1, at 45. The lower end of each arm 44 is connected to the adjacent arm 18 for oscillation therefrom, so that the upper end of arm 44 reverses the movement of arm 18.

The upper end of each arm 44 is connected by appropriate linkage to the frame 40. As 90 shown, a link 46 is pivotally connected at one end to the upper end of an arm 44, and at the other end to a link 47, the other end of which is pivoted to one end of a link 48, the other end of which is pivotally 95 connected to the frame 40. In operation, the alining device moves forwardly when the forward movement of the carrier stops and pawls 8 and arms 18 begin their return movement, roller 37 resting against a point 100 on cam 38 one half revolution distant from that shown in Fig. 1. During the forward movement of the alining device, cross-member 32 is somewhat raised, but moves downwardly in accordance with the shape of cam 105 38, so that the lower ends of fingers 41 are in position to press against the cakes. The fingers extend somewhat between the cakes, as shown in Fig. 5, press forwardly any 110 cakes that are not sufficiently advanced, and also move sidewise any that are too close together, so as to locate them at equal distances apart. The next forward movement of the carrier brings them exactly under the spouts of the depositing device. The 115 carrier starts to move forward, from the position shown in Fig. 1, fingers 41 rise somewhat, and move back over the next row of advancing cakes.

A modification of the apparatus is illustrated in Fig. 6, in which a hopper 20¹ for candied fruit or the like is shown in advance of the hopper 20 for the marshmallow or icing, it being understood that hopper 20¹ is adapted to discharge material onto 120 the cakes from a row of spouts similar to and equal in number to the spouts 22 of hopper 20 (Fig. 2). In the form shown, the cranks 18 are oscillated by connection 125 with arms 9 as in the form previously de- 130

scribed, the pivoted arms 44¹ being oscillated to reverse the movement of cranks 18 by links 49 connecting the lower ends of arms 44¹ with cranks 18, substantially in the same manner as described in connection with arms 44 in the form of construction already described. Links 49 may be provided with slots 50 and arm 44¹ with screws 51 engaged therein, for adjustment.

10 Arms 44¹ are connected, at their upper ends, by pivoted links 52, one at each side of the machine, with horizontal bars 53, which are slidably mounted, as by screw and slot connections 54, 55, on the vertical side frame members 56, 56, of the hoppers 20, 20¹. The alining frames 40, having depending fingers 41, one frame for each hopper, are secured to bars 53 for horizontal reciprocation, and are connected to cross-members 32, 32, of the depositing devices for vertical movement, members 32 moving preferably in the same manner as the members similarly numbered in the form of our device first described. This may be accomplished by providing each frame 40 with a pair of sleeve portions 42¹, which are arranged to slide on arms 57 which are secured to the vertically movable cross-members 32, and by connecting frames 40 with bars 53 by means of links 58, 58, which are pivoted at their opposite ends to frames 40 and bars 53. Preferably links 58 are pivoted to bars 53 by screws which are secured at desired points in slots 59 in bars 53, to provide for adjustment.

With this construction, it will be evident that alining frames 40 for both depositing devices move forward and back with bars 53, and up and down at appropriate times 40 with members 32, the angular positions of links 58 being such that frames 40 will reciprocate with bars 53, while at the same time links 58 oscillate about their upper ends as members 32 move up and down. 45 The timing of the movements of the two frames 40 in relation to the movements of the depositing devices and the carrier may be the same as that of the frame 40 described in connection with the first form of our device.

It will be understood that our invention is not limited strictly to the exact details of construction described, but is as broad as is indicated by the accompanying claims.

55 What we claim is:

1. In a depositing machine, the combination of a traveling carrier, means for advancing the same step by step, mechanism for depositing material on a row of cakes across the carrier, after each advance of the latter, having a vertically reciprocating member, an alining device for the cakes, means for moving the same forward and back while the carrier is stationary and is moving forward, and means connected with

said vertically reciprocating member of the depositing mechanism for lowering the alining device as it approaches the cakes to be adjusted and for raising the same as it moves back therefrom. 70

2. In a depositing machine, the combination of a traveling carrier, means for advancing the same step by step, mechanism for depositing material on a row of cakes across the carrier, after each advance of the latter, an alining device for the cakes, and means, operatively connected to the carrier-advancing means, for moving the same forward, while the carrier is stationary, to aline the row of cakes one step in the rear 80 of the depositing mechanism, and for raising the same and returning it to its starting point while the carrier is moving forward, continuously during the operation of the machine, the carrier advancing the row of 85 cakes thus alined, beneath said depositing mechanism on the next forward movement of said carrier.

3. In a depositing machine, the combination of a traveling carrier, a pawl and 90 ratchet device for advancing the same step by step, mechanism for depositing material on a row of cakes extending across the carrier, after each advance of the latter, an alining device for the cakes, a lever pivoted 95 intermediate its ends, connections for moving one end of said lever back and forth with the pawl of said pawl and ratchet device, actuating connections between the other end of said lever and said alining 100 device, and means for raising and lowering said device during its reciprocation.

4. In a depositing machine, the combination of a traveling carrier, means for advancing the same step by step, depositing 105 mechanism, having a member which moves down and up during each forward movement of the carrier and the succeeding interval, an alining device, to aline a row of cakes to receive a deposit, a longitudinally extending sleeve secured to said device, a rod secured to said member and slidably extending in said sleeve, and means, adapted to permit the raising and lowering of said device, for reciprocating the same 110 during the actuation of the machine.

5. In a depositing machine, the combination of a traveling carrier, depositing mechanism, having a vertically reciprocating member, an alining device, to aline a row 120 of cakes to receive a deposit, means for moving the same forward and back, and means operatively connected with said vertically reciprocating member of the depositing mechanism for raising and lowering the 125 alining device during its reciprocation.

6. In a depositing machine, the combination of a traveling carrier, depositing mechanism, having a vertically reciprocating member, an alining device, to aline a row 130

of cakes to receive a deposit, carrier - advancing means, means, operatively connected to the carrier - advancing means, for moving said alining device forward and back, and means operatively connected with said vertically reciprocating member of the depositing mechanism for raising and lowering the alining device during its reciprocation.

10 7. In a depositing machine, the combination of a traveling carrier, a pair of depositing mechanisms spaced apart above the same, each having a vertically-reciprocating member, a pair of alining devices, to aline 15 rows of cakes to receive deposits from said

mechanisms, means connecting said alining devices, means for moving the same forward and back, and means operatively connected with said vertically-reciprocating members of said depositing mechanisms for raising 20 and lowering said alining devices during their reciprocation.

This specification signed and witnessed this 23rd day of August, 1918.
